UNITED STATES PATENT OFFICE.

JAMES F. HARTMAN, OF FALL RIVER, MASSACHUSETTS, ASSIGNOR TO THE STAFFORD COMPANY, OF BOSTON, MASSACHUSETTS, A CORPORATION OF MASSACHUSETTS.

FEELER TIP FOR SIDE-SLIPPING FEELERS.

Application filed June 29, 1923. Serial No. 648,485.

The invention has relation to depletion indicating devices for looms, of the class commonly known as filling-feelers. As is well known, a device of such class has a filling-engaging portion or tip which is adapted to enter the shuttle in use upon a loom, to test or "feel" the wound mass of filling upon the filling-carrier carried within the shuttle to ascertain whether it has become substantially exhausted.

The invention has for its object to provide a filling-engaging portion or tip having an improved action in its engagement with the filling-mass within a shuttle, and less liable to injure the filling than the toothed contact-portions or tips of the filling-feelers at present in use.

The invention consists in a feeler tip or filling-engaging portion comprising one or more unyielding contact-portions, or teeth normally making engagement with the turns of filling upon the filling-carrier in a feeling action and adapted to become embedded among said turns and one or more yielding contact-portions laterally adjoining in an alternating series and adapted to make contact with turns projecting relative to the said teeth. It consists further in features of construction which hereinafter are described and are pointed out in the claims. The said yielding contact-portion or portions may advantageously be made of frictional material, especially in the case of a tip forming an element of a side-slipping feeler-mechanism.

The invention is applicable in connection with feelers of various classes, both slipping and non-slipping. It is especially applicable in the case of side-slipping feelers of the various known types.

An illustrative embodiment of my invention is shown in the accompanying drawings combined with a filling-feeler of the side-slipping class, and modifications of the feeler tip construction are shown in separate views. In the drawings,—

Fig. 1 is a plan view of the said filling-feeler having the said illustrative embodiment of the invention combined therewith, and also portions of the lay-beam of a loom, and of one of the shuttle-boxes of the lay, a shuttle occupying said shuttle-box and a filling-carrier within the said shuttle.

Fig. 2 is a plan view of the feeler tip of Fig. 1.

Fig. 3 is a view of the working end thereof, looking from the right in Fig. 2.

Fig. 4 is a view of the said feeler tip partly broken away and partly in horizontal section.

Figs. 5 and 6 show tips of modified construction.

Having reference to the drawings,—

A small portion of the lay-beam 1 is shown in Fig. 1, 2 being the front-plate of the shuttle-box upon that end of the lay-beam which is adjacent the feeler-mechanism, and 4 a shuttle occupying the said shuttle-box. The said front-plate and the front wall of the shuttle have the usual openings 21, 41, 70 to permit entrance of the filling-engaging portion or tip 5 of the feeler mechanism as the lay beats up, to provide for contact between the said tip 5 and the wound mass of filling 6 upon the filling-carrier 7 occupying the shuttle 4, each time the lay 1 advances with the shuttle in the shuttle-box at the end of the loom at which the feeler mechanism is positioned.

As already indicated, my invention is shown in Fig. 1 combined with feeler mechanism which works on the side-slipping principle, and in the illustrated instance the said mechanism is of the type in which the filling-engaging portion or tip 5, which enters the shuttle 4, and contacts with the contents thereof, is offset with respect to the pivotal point 51 of connection of the feeler-member 9 with the forwardly and rearwardly movable yielding support 8. The said support, as usual, is normally held rearward through the expansion of its actuating spring 9'. As will be understood, the said filling-engaging portion tends to slip sidewise under the push of the advancing shuttle-contents as the lay comes forward in beating up.

In practice, the contacting rearward face of the filling-engaging portion or tip of a side-slipping feeler-device is usually roughened or serrated, or otherwise adapted to make firm frictional engagement with the turns of filling 6, so as to prevent lateral slipping movement of the feeler-member so long as any substantial amount of wound filling remains upon the filling-carrier 7 within the shuttle, but is intended to slip sidewise along the surface of the filling-carrier 7 when the latter has become practically denuded. This sidewise slipping movement is utilized through suitable con-

nections with the change-calling devices of the loom to stop the weaving or to initiate automatic filling replenishment, as the case may be. In the illustrated instance the forwardly extending arm 91 of the feeler-member 9 is connected by means of wire 11 with the said change-calling devices (not shown).

It has been found in practice that filling-engaging portions or tips of metal and other hard substances, especially when provided with roughened or toothed surfaces, have a tendency to cut and wear the yarn wound on the filling-carrier at the point where the impact falls, as the result of repeated contacts. This is particularly true when using fine yarns for weft, inasmuch as the yarn is relatively weak and easily cut and frayed, and also the turns or coils with which the tip 10 makes contact are exposed to its action for a long period of time, since the filling-carrier holds a relatively great length of fine yarn, which will run for quite a while.

My invention makes it possible to retain 25 the advantages of the toothed construction of feeler tips without having the usual drawback of injury to the yarn.

In accordance with my invention, the toothed feeler-tip 5, formed with teeth 52, 30 52, for engagement with the wound filling within the shuttle, has combined therewith a cushion 10 which contacts with the filling alongside the said teeth until the wound mass upon the filling-carrier 7 becomes substantially depleted. In Figs. 1 to 4, the cushion is simply and cheaply provided by drilling a hole 53 laterally through the extreme rearward end of the filling-engaging portion or tip 5 at the bases of the teeth 52, 35 52, and drawing into this bore a tight-fitting cord of yarns either laid or twisted. The slots between the teeth 52, 52, intersect the said hole, and expose the said cord between the teeth. Other materials of a resilient, 40 cushioning, nature may equally well be used, such as rubber or fabric. Or, in other instances, I may employ cushioning material to fill the voids between the teeth by merely winding such material around the rearward 45 end of the tip 5, as at 100 in Fig. 5, in which case the said end is spirally grooved to form the teeth and accommodate the wound material. In still other instances, the action of the toothed feeler-tip may be obtained by 50 applying a piece 101, Fig. 6, of resilient or cushioning material to the rearward face of a feeler tip which has no teeth, and securing such cushion by transverse windings of coarse wire 102 with the turns relatively 55 widely spaced. In this latter arrangement, the turns of wire act as teeth to engage with the turns of filling just as do the teeth of a feeler tip of the illustrated type.

The cushion of resilient material substantially fills the gaps between the teeth, but

permits the teeth to engage well with the filling-mass 6, and become embedded between the turns of filling in a feeling action while at the same time the cushion 10 is receiving a large portion of the impact of the 70 said filling-mass 6 and softening the blow, as well as limiting the penetration of the teeth. Also, by this arrangement the teeth are permitted to contact with the hard surface of the filling-carrier 7 when it has become bare or substantially bare, so as to slide freely thereon in accordance with the intended side-slipping action and call the change.

I claim as my invention,—

1. In filling-feeler mechanism for looms, a side-slipping feeler tip having teeth normally making engagement with the turns of filling upon the filling-carrier in a feeling action and adapted to embed themselves among said turns, and non-metallic cushioning material disposed adjacent such teeth and adapted to make contact with turns projecting relative to the said teeth. 80

2. In filling-feeler mechanism for looms, a side-slipping feeler tip having teeth normally making engagement with the turns of filling upon the filling-carrier in a feeling action and adapted to embed themselves among said turns, and fibrous cushioning material disposed adjacent such teeth and adapted to make contact with turns projecting relative to the said teeth. 95

3. In filling-feeler mechanism for looms, a side-slipping feeler tip having teeth for engagement with the turns of filling upon the filling-carrier, and cushioning material between the said teeth. 100

4. In filling-feeler mechanism for looms, a side-slipping feeler tip having teeth for engagement with the turns of filling upon the filling-carrier, and cushioning material underlying the said teeth and filling the spaces between the teeth. 105

5. In filling-feeler mechanism for looms, a side-slipping feeler tip having teeth for engagement with the turns of filling upon a filling-carrier, and cushioning material between the said teeth adapted to engage the said turns of filling without contact with the filling-carrier when the latter becomes bare. 110

6. In filling-feeler mechanism for looms, a side-slipping feeler tip having teeth for engagement with the turns of filling upon a filling-carrier, and cushioning material exposed between the said teeth, the latter projecting beyond the cushioning material. 120

7. A feeler-tip having a laterally extending hole in its working end and slots in its working face intersecting said hole, with teeth between said slots, and cushioning material occupying said hole and exposed at such slots for contact with the filling upon a filling-carrier in the feeling operation. 125

8. In filling-feeler mechanism for looms, a feeler-tip comprising unyielding contact-portions and non-metallic yielding contact-portions laterally adjoining in an alternating series, said yielding contact-portions adapted to engage filling entering between the unyielding ones in a feeling action.

9. In filling-feeler mechanism for looms, a side-slipping feeler-tip comprising unyielding contact-portions and non-metallic yielding contact-portions, laterally adjoining in an alternating series, said yielding contact-portions adapted to engage filling entering between the unyielding ones in a feeling action, and the unyielding contact-portions adapted to slip upon the surface of a yarn-carrier.

10. A feeler-tip comprising one or more engaging and detaining projections normally embedding in the turns of filling in a 20 feeling action and one or more laterally adjoining cooperating cushions of non-metallic yielding material adapted for contact with turns projecting relative to said projection or projections.

11. A feeler-tip comprising one or more engaging and detaining projections normally embedding in the turns of filling in a 30 feeling action and one or more laterally adjoining cooperating cushions of non-metallic frictional material adapted for contact with turns projecting relative to said projection or projections.

JAMES F. HARTMAN.
